(57) **CLAIM**

The ornamental design for a cluster jet, as shown and described.

DESCRIPTION

FIG. 1 is a perspective view of the cluster jet of the present design.

FIG. 2 is a left side elevation view of the design of FIG. 1.

FIG. 3 is a bottom plan view of the design of FIG. 1.

FIG. 4 is a top plan view of the design of FIG. 1.

FIG. 5 is a right side elevation view of the design of FIG. 1.

FIG. 6 is a front elevation view of the design of FIG. 1; and,

FIG. 7 is a rear elevation view of the design of FIG. 1.

The broken line showing portions of a cluster jet is included for the purpose of illustrating environmental structure and forms no part of the claimed design.

The Dash Dash lines immediately adjacent to the full line as seen in FIGS. 1 and 4 in the nozzle represent the boundaries of the claimed design. None of these dashed lines from any part of the claimed design.
